UNITED STATES PATENT OFFICE.

GEORGE M. LAUB, OF NEW YORK, N. Y., ASSIGNOR TO MAY MANTON PATTERN COMPANY, OF NEW YORK, N. Y., A CORPORATION OF NEW YORK.

PAPER PATTERN.

No. 852,382.

Specification of Letters Patent. Patented April 30, 1907.

Application filed July 11, 1906. Serial No. 325,710.

To all whom it may concern:

Be it known that I, GEORGE M. LAUB, a citizen of the United States, and a resident of New York city, New York, have invented 5 certain Improvements in Paper Patterns, of which the following is a specification.

My invention relates to patterns, usually of paper, though other material may be used, employed in connection with the cutting of 10 fabrics preliminary to the making of dresses or other garments, and it consists of certain improvements in keying means for identifying the several sections of such patterns whereby the use of the same is greatly facilitated. 15

My invention is fully shown in the accompanying drawings, in which:

Figure 1, illustrates a group of independent sections forming a single pattern; Fig. 2, 20 is a section of such pattern embodying my invention, and Figs. 3 and 4, are views illustrating details of my invention.

My invention consists in providing each 25 section of a pattern with keying means, by displaying upon the same some readily distinguishable mark or symbol common to each section of the pattern together with certain instructions respecting the use of the patterns or the several sections of the same; 30 as, for instance, the name of the individual section, and the name of the garment for which the pattern is designed. The printed matter in every instance is in several languages.

By preference the various legends printed 35 or otherwise displayed upon the several sections of the pattern are inclosed in a suitable frame or panel 1, which is divided into the spaces 2, 3 and 4. Space 2 contains the reference to the measurement forming the common mark or symbol of the pattern, such as 40 that of the "bust" or "waist," or other measurement suitable for the purpose, as the case may be. Space 3, contains the identification of such measurement as the word "bust" or "waist," as the case may be, in the several languages, and space 4, contains the name or title of the particular pattern 45 section and such other instructions as may be 50 desirable.

The measurement indicated in numerals in space 2 will be that usually employed in keying patterns. For instance, if the pattern is

for a waist or similar garment for the upper part of the body, the "bust" measurement 55 will be indicated, while if the pattern is for a skirt or other similar garment, the "waist" measurement will be indicated. In every instance, the several sections of the different patterns will carry this common identifying 60 mark or symbol.

Below the common identifying mark or symbol is the other printed matter identifying the section of the pattern. For instance, Fig. 2, represents a cuff section belonging to 65 a pattern for a waist, coat or similar garment having a bust measurement of 36 inches, and in the space 4, at the lower portion of the panel, the word "cuff" is printed in the several languages. 70

In Fig. 4, I have shown a modification of my invention, in which, in addition to the marks identifying the sections of the pattern, I have added the space 5 to contain the name of the garment of which the pattern section is 75 a part, which name is also printed in several languages.

This marking of the several sections of a pattern is of great value at various times. It facilitates the ready assembling of independent patterns of the same size, or the same patterns of different size by the manufacturer, with the assurance, when such patterns are inclosed in their proper envelopes, that all of the several sections of the different patterns are properly arranged. It is of especial value to the user when a number of patterns are kept on hand, as each section is 80 positively identified and the parts can be readily kept together. It is further of material value should a person be desirous of cutting two or more garments of different size from the same material. Similarity of the several sections of such patterns, differing but slightly in size, would tend to certain 85 confusion, but by having each section marked with the identification matter, there can be no mistake and it will be as easy to cut two patterns of the same general style 90 from the same material as it is to cut one. 100

I claim:

1. In garment patterns, sections of the same, each section having an identifying mark or symbol common to all the sections.
2. In garment patterns, sections of the same, each section having an identifying

mark or symbol common to all the sections, the name of the section and instructions for its use, displayed thereon.

3. In garment patterns, sections of the same, each section having an identifying reference mark or symbol common to all the sections and consisting of a number representing the "bust" "waist" or other measurement of the garment for which the pattern is intended, such number being employed as a key.

4. In garment patterns, sections of the same, each section having an identifying reference mark or symbol common to all the sections and consisting of a number representing the "bust," "waist" or other measurement of the garment for which the pattern is intended, such number being employed as a key, in combination with the name of the part of the garment each pattern section represents.

5. In garment patterns, sections of the same, each section having an identifying reference mark or symbol common to all the sections and consisting of a number representing the "bust," "waist" or other measurement of the garment for which the pattern is intended, such number being employed as a key.

urement of the garment for which the pattern is intended, such number being employed as a key, in combination with the name of the part of the garment each pattern section represents, such data being printed in several languages.

6. In garment patterns, sections of the same, each section containing a common identifying reference mark or symbol consisting of a number representing the "bust," "waist" or other measurement, in combination with the name of the section, the name of the garment of which it is a pattern section, and instructions for its use, the whole being shown in several languages in a frame or panel suitably displayed upon each section, and the data of the respective items separated by dividing lines.

In testimony whereof, I have signed my name to this specification, in the presence of two subscribing witnesses.

GEORGE M. LAUB.
